(57) **CLAIM**

The ornamental design for a combination notebook computer with auxiliary lighting fixture, as shown and described.

DESCRIPTION

FIG. 1 is a perspective view of a combination notebook computer with auxiliary lighting fixture showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is the perspective view of FIG. 1, showing a lighting part of the combination notebook computer with auxiliary lighting fixture in an illuminated state.

(Continued)

The dashed broken lines illustrate portions of the combination notebook computer with auxiliary lighting fixture that form no part of the claimed design. The dot-dash broken lines represent the boundaries of the claimed design, and form no part thereof. Unshaded surfaces form no part of the claimed design. The radiating lines in FIG. 8 illustrate the glowing visual effect created by light emanating from the light part of the combination notebook computer with auxiliary lighting fixture, and form no part of the claimed design.
